UNITED STATES PATENT OFFICE.

GEORGE F. McCOMBS, OF ALLEGHENY, ASSIGNOR TO THE HAND STITCH BROOM SEWING MACHINE COMPANY, OF PITTSBURG, PENNSYLVANIA.

BROOM-CORN-SIZING MACHINE.

SPECIFICATION forming part of Letters Patent No. 517,761, dated April 3, 1894.

Application filed June 3, 1893. Serial No. 476,497. (No model.)

To all whom it may concern:

Be it known that I, GEORGE F. McCOMBS, a citizen of the United States, residing at Allegheny, in the county of Allegheny and State of Pennsylvania, have invented or discovered certain new and useful Improvements in Broom-Corn-Sizing Machines, of which improvements the following is a specification.

The invention described herein relates to 10 certain improvements in machines for sorting broom corns, and has for its object a construction whereby the broom corn may be easily and quickly separated into lengths suitable for the manufacture of various sizes of 15 brooms and whisks, and the several sizes deposited into their respective bins.

In general terms, the invention consists in the construction and combination substantially as hereinafter more fully described and 20 particularly claimed.

In the accompanying drawings forming a part of this specification, Figure 1 is a perspective view of a machine embodying my improvement. Fig. 2 is a top plan view of the 25 same. Fig. 3 is a sectional elevation, the plane of section being indicated by the line α, α , Fig. 2. Fig. 4 is a sectional elevation, the plane of section being indicated by the line y, y , Fig. 3. Fig. 5 is an enlarged sectional view of a portion of the cutting mechanism. Fig. 6 is a detail view, partly in section and partly in elevation, of the cutting mechanism, the plane of section being indicated by the line v, v , Fig. 4. Fig. 7 is a trans- 35 verse section of the box portion of the machine, showing the adjustment of one of the gage plates, and Fig. 8 is a sectional detail view of a portion of the adjustable gage plate.

The box 1 is divided by a series of partitions 2, into a series of bins 3, for the reception of different sizes of broom corns. At the ends of the box are secured suitable bearings 4, for the shafts 5 and 6, on which are secured a series of pulleys 7 and 8, over which pass 45 the belts 9, provided with a series of projecting pins adapted to carry along the broom corn, as hereinafter described. The pulleys 7 and 8 are made of such a size that the under portions of the belts 9 will move along in 50 close proximity to or upon the gage plates 10

and 11, secured along the sides of the open top of the box. As shown in Fig. 2, the plate 10 is made of a uniform width and is non-adjustably secured to the box. The plate 11 is made of varying width or provided with a series of notches of varying depth, along its inner edge. As shown in Figs. 4 and 7, this plate 11 is laid loosely upon the top of the box, being held from vertical movement by means of brackets 13, provided with flanges 14, which project into slots in the ends of the plate 11. These brackets hold the plate as against vertical movement, but permit its lateral movement toward and from the plate 10, by means of screws 15, which enter threaded openings in the outer edge of the plate 11, and are held as against movement by brackets 16, secured to the side of the box.

On the shaft 5, and in line with the gage plate 10, are secured disks 17, provided with a series of projecting teeth and between these disks 17 is secured a cutter disk 18. On a shaft 19 below the shaft 5 and parallel therewith, is secured a disk 20, provided with a peripheral cutting rim 21. This shaft 19 is 75 free not only to rotate in its bearings, but also to move longitudinally, so that the cutting rim 21 of the disk 20 may be held tightly against the cutting blade 18, by the spring 22 surrounding the shaft 19, and bearing at its 80 ends against one of the bearings of the shaft 19, and a nut or shoulder on said shaft. By reference to Fig. 5, it will be seen that the blade 18 and cutting portion 21 of the disk 20 are slightly recessed, just back of their cutting edges, so that as such edges rub together, 85 they will sharpen each other.

The broom corn as brought to the factory has a longer stem than is required in the manufacture of brooms, and the straws vary in 90 length as hereinbefore stated. In sorting the broom corn the stalks of the latter are laid on the table at the front end of the machine, in such position in front of the cutting knives that, as the broom corn is caught by the projecting teeth on the disks 17, and also on a disk 23 on the shaft 5, the broom corn will be 95 drawn in between the knives, and the excess thereof cut off. Simultaneously, the pins or spurs on the belts 9 catch the broom corn and 100

draw it along over the gage plates 10 and 11, the stalk end resting on the continuous plate 10 and the wisp end upon the notch plate 11. As the broom corn traverses along these 5 plates, it will reach one of the notches through which the wisp end will drop, at the same time the stalk end will be drawn off the plate 10. Immediately below each notch in the plate 11, is located one of the bins, and at the 10 upper end of these bins are arranged inclined guide plates 24 and 25 against which the wisp end of the broom corn will drop first, thereby delaying the downward movement of the wisp end sufficiently to permit the stalk end to 15 overtake it, so that the broom corns will lie properly arranged with their wisp ends outward in the bins. If the depth of the bins is considerable, the broom corns are liable when dropping one by one, to fall irregularly into 20 the bottom of the bin, but if dropped in a large mass, they will preserve their regular arrangement. To effect this, swinging doors 26 are arranged so as to close the opening between the converging ends of the plates 24 25 and 25, so as to retain the broom corns in the pockets thus formed until a large number have been collected, and then drop them *en masse*. These doors are connected to a common operating rod extending to the front of 30 the machine, so that they may be operated simultaneously.

It is characteristic of my improvement that the employment of fingers or projections adjacent to the cutting blades permits of the rotation of said blades at a lower rate of speed than has heretofore been practicable with 35 this class of machines.

It is a well known fact that in some years

the broom corns grow to a greater average than in other years, so that a sorting machine 40 such as described would not be capable of use at all times. But, by forming one of the gage plates in such manner as to permit of its adjustment, the machine is capable of use on all kinds of broom corn. 45

I claim herein as my invention—

1. In a broom corn sizing machine, the combination of overlapping rotating cutting blades one of said blades being recessed back of its cutting edge, a spring for holding the 50 cutting edges of the blades in contact with each other and rotating disks provided with fingers for feeding the broom corn between the cutting blades, substantially as set forth.

2. In a broom corn sorting machine, the 55 combination of overlapping rotating cutting blades, rotating disks arranged on opposite sides of one of the cutting blades and provided with fingers overlapping the periphery of the other cutting blade, substantially as set forth. 60

3. In a broom corn sorting machine, the combination of rotating cutting blades, a series of movable fingers on one side of the cutting blades operative on the body of the broom corn, and a series of movable fingers on the 65 opposite side of the cutting blade, said series of fingers moving in unison, whereby the broom corn is fed squarely to the cutting blades, substantially as set forth.

In testimony whereof I have hereunto set 70 my hand.

GEORGE F. McCOMBS.
